UNITED STATES PATENT OFFICE.

JOSEPH B. ALTEMUS, OF PHILADELPHIA, PENNSYLVANIA, ASSIGNOR TO HIMSELF AND LEMUEL COFFIN, OF SAME PLACE, AND EDWARD A. TREAT, THOMAS B. MARTIN, AND EVERETT H. CONVERSE, OF NEW YORK, N. Y.

DESIGN FOR PRINTED FABRICS.

Specification forming part of Design No. **11,334**, dated August 19, 1879; application filed May 31, 1879.
[Term of patent 14 years.]

To all whom it may concern:

Be it known that I, JOSEPH B. ALTEMUS, of Philadelphia, Pennsylvania, have produced or invented a new and original Design for a Printed Fabric, of which the following is a specification.

My design for a printed textile fabric is fully shown in the accompanying drawing.

The design comprises representations of parts of a lady's dress or wrapper, *a* being one-half of the front of the dress; *b*, one-half of the back of the same; *d d*, the opposite halves of one of the sleeves, and *e* a pocket.

The different parts are ornamented with bands or stripes, the character and arrangement of which are too fully shown in the drawing to need description.

Irrespective of the colors employed, I claim—
The design for a printed textile fabric, said design comprising representations of parts of a lady's dress or wrapper, ornamented with bands or stripes, all substantially as described, and as shown in and by the accompanying drawing.

In testimony whereof I have signed my name to this specification in the presence of two subscribing witnesses.

J. B. ALTEMUS.
